(57) **CLAIM**

The ornamental design for a display screen with transitional graphical user interface, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first image in a sequence for a display screen with a transitional graphical user interface with dual arcs showing a first embodiment of our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a six image thereof;

FIG. 7 is a front view of a first image in a sequence for a display screen with a transitional graphical user interface with dual arcs showing a second embodiment of our new design;

FIG. 8 is a front view of a second image thereof;

FIG. 9 is a front view of a third image thereof;

FIG. 10 is a front view of a fourth image thereof;

FIG. 11 is a front view of a fifth image thereof; and,

FIG. 12 is a front view of a six image thereof.

The broken line at the periphery of the figures illustrates a display screen, and the remainder of the broken lines illustrate portions of the user interface. None of the broken lines form part of the claimed design. The shading in FIGS. 7-12 depicts contrasts in appearance of the transitional graphical user interface. The subject matter in this patent includes a process or period in which an image changes into another image. This process or period forms no part of the claimed design.
